UNITED STATES PATENT OFFICE

CHOICE R. HARPER, OF KNOX CITY, TEXAS, ASSIGNOR OF ONE-THIRD TO JACK WATKINS, OF WINK, TEXAS

UNDERGROUND VALVE FOR OIL WELLS

Application filed September 20, 1929. Serial No. 394,121.

The object of the invention is to provide a valve structure for location in oil well casings which will be automatically opened on the lowering of the working valve and during the operation of the latter and automatically closed when the working valve and tubing are withdrawn, thus providing in a high pressure well, a means for preventing the flow of oil through the tubing while the same is being pulled and also preventing the escape of gas from the well with its attendant danger to the workmen; to provide a valve of this nature which is spring actuated to either its open or closed position; and to provide a valve structure of this nature which is generally of simple form, so as to be susceptible of cheap manufacture and low marketing cost.

With this object in view the invention consists in a construction and combination of parts of which a preferred embodiment is illustrated in the accompanying drawings, wherein:

Figure 1 is an elevational view, partly in section, illustrating the invention.

Figure 2 is a central vertical sectional view on the plane indicated by the line 2—2 of Figure 1.

Figure 3 is a view similar to Figure 2 but showing the valve in open position.

Figures 4 and 5 are transverse sectional views on the planes indicated by the lines 4—4 and 5—5 respectively of Figure 2.

The invention comprises a housing 10 adapted for location in the well casing 11 and provided just above its intake end 12 with an interior annular rib 14, tapered as indicated at 15, to provide a conical seat for the correspondingly shaped lower end 16 of the valve casing 17. The casing 17 at its upper end is machined as indicated at 18 to provide a cylindrical portion located in and snugly engaging the face of an annular rib 19 on the interior of the housing 10 which, above this rib 19 is interiorly threaded for the reception of the lower exteriorly threaded end 20 of a cap member 21 which, when engaged with the housing 10 at the upper end, has its lower end bearing on the upper end of the casing 17. The upper end of the casing 17 is beveled to provide a conical seat for the lower

end of the threaded portion 20 of the cap 21. The engaging faces between the lower portion 16 of the casing 17 and the cap 15, as well as the contacting faces between the parts 19 and 18 and the upper end of the casing 17 and lower end of the threaded extension 20 are ground fits, so as to preclude leakage when the parts are assembled.

Just above the lower conical portion 16, the casing 17 is of globular formation and located within this globular chamber 22 is a disk valve 23 which is adapted to assume either of two positions in one of which it is disposed transversely across the casing 17 when it engages the seat 24 and encloses communication through the casing 17. In the other position, the disk valve lies in a plane parallel to the axes of the casing, thus opening communication through the latter.

The disk valve 23 is pivotally mounted and to this end is provided with a pair of spaced ears 25 from the outer faces of which project pivot studs 26 pivotally mounted in the spaced side walls of a lateral extension 27 of the casing 17. The ears are spanned by pins 28 and 29 disposed on opposite sides of the pivots 26 and to the former is pivotally connected a link member 30 and to the latter one end of a tension spring 31 whose other end is anchored at a fixed point as indicated at 32 within the extension 27. In the movement of the disk valve 23 to its open and closed positions, the spring crosses the axes of the pivot studs 26 so that it is double acting to yieldingly hold the valve in either of the two positions.

The link member 30 is preferably cross-sectionally circular and enters the extension 27 of the casing 17 through a stuffing box 33, passing through a second stuffing box 34 into another extension 35 of the casing 17 in which it is pivotally connected as indicated at 36 to a trip lever 37 which is pivotally mounted in the extension 35 of the casing 17, as indicated at 38. Since the link member 30 has pivotal connections both with the valve 23 and trip lever 37, it is made comparatively small in cross section so as to spring in the changing positions of the pivots

as the valve is moved from open to closed position and vice versa.

With the valve 23 in closed position, as indicated in Figure 2, the free end of the lever 37 is in the upper end of the extension 35 of the casing 17, so as to be out of obstructing position to the working valve 39 when the latter is lowered. When the working valve reaches the valve 23, it unseats the latter and after this valve has moved to a position where the spring 31 passes the pivot studs 26, the spring completes the opening operation, when the free end of the lever 37 is shifted to the bottom side of the extension 35. During the pumping operation, the working valve operates below the plane of the lever 37, so there is no tendency to change the open position of the valve 23. When the working valve and the tubing are withdrawn, however, it is the purpose to have the valve 23 closed, so that there may be no passage of oil or gas up the well tube. The elevation of the working valve 39 brings the shouldered portion 40 into engagement with the free end of the lever 37, when the latter is rocked on its pivot, thus swinging the valve 23 to closed position by reason of the link connection between the lever and the valve, the spring 31 completing the closing operation immediately after it has passed the centers of the pivots 26.

The invention having been described what is claimed as new and useful is:

1. In combination with the working valve of an oil pumping apparatus, a safety valve actuated to open or closed position respectively by the working valve in lowering the latter into or withdrawing it from the well.
2. In combination with the working valve of an oil pumping apparatus, a safety valve spring actuated to open and closed positions, and means for effecting movement of the safety valve, said means being actuated by the working valve to close the safety valve when the working valve is withdrawn and actuated by the working valve to open the safety valve when the working valve is lowered into the well.
3. In combination with the working valve of an oil pumping apparatus, a casing through which the working valve moves, a safety valve controlling communication through said casing, and means actuated by the working valve for shifting said valve into its closed position when the working valve is withdrawn.
4. In combination with the working valve of an oil pumping apparatus, a casing through which the working valve moves, a safety valve controlling communication through said casing, and means actuated by the working valve for shifting said safety valve into its open and closed positions, said means comprising a spring, and a lever having a link connection with said safety valve

and engageable by the working valve to close the safety valve when the working valve is withdrawn, said safety valve being directly engageable with the working valve for movement to open position when the working valve is lowered into the well.

In testimony whereof he affixes his signature.

CHOICE R. HARPER.
